(57) **CLAIM**

The ornamental design for a portion of a motorcycle air cleaner cover and tire, as shown and described.

DESCRIPTION

FIG. 1 is a side view of a portion of a motorcycle air cleaner cover and tire embodying the present invention while in use; and,

FIG. 2 is an enlarged side view of a portion of the design illustrated in FIG. 1.

The top, bottom, front, and rear views are not part of the claimed design. The broken line showing of the environment is for illustrative purposes only and forms no part of the claimed design.
